LLP

(57) CLAIM

The ornamental design for a table lamp, as shown and described.

DESCRIPTION

1. Table lamp
1.1 is a top perspective view;
1.2 is a bottom perspective view;
1.3 is a side view;
1.4 is a side view;
1.5 is a top view; and
1.6 is a bottom view.
The model regards a table lamp with a base, a supporting rod vertically protruding from the base, a lighting cap, and a transparent shade supported by the cap.

1 Claim, 6 Drawing Sheets
